UNITED STATES PATENT OFFICE.

WILHELM KOLMER AND ERHARD WIRSCHINGER, OF AUGSBURG, GERMANY, AS
SIGNORS TO MASCHINENFABRIK AUGSBURG-NUERNBERG, AKTIENGESELLSCHAFT,
OF AUGSBURG, GERMANY, A CORPORATION OF GERMANY.

ROLLER-INKING APPARATUS FOR FAST PRINTING PRESSES.

Application filed April 22, 1926, Serial No. 103,816, and in Germany May 26, 1925.

There are well known roller inking-apparatus for fast printing presses which consist of a set of preliminary distributing rollers rotating uniformly in one direction and a set of inking rollers operated by the printing carriage and rotated in two directions according to the direction of travel of said printing carriage. The ink or colour is transferred from the preliminary distributing or working up set to the inking roller set by a vibrator roller. This well known arrangement has the disadvantage that the vibrator roller having the same diameter as the inking roller cannot pick up the amount of ink required for one printing from the preliminary distributing roller set and transfer same to the inking roller set, without the thickness of the ink layer becoming greater than is desirable for effecting a uniform transfer.

It has been proposed in order to increase the taking up capacity of the vibrator roller to make the diameter of this roller equal to a multiple of the diameter of one of the inking rollers. In that case, however, the vibrator roller can make only one or at the utmost two revolutions whilst taking up ink from the preliminary distributing roller set. The benefit derived from the enlargement of the peripheral surface of the vibrator roller is therefore offset by the disadvantage of such a large vibrator roller being incapable of acting as a distributing roller to the same extent as a small vibrator roller. Moreover, large vibrator rollers are as a rule to be avoided in roller inking-apparatus because of the increased space which they require.

The above described defects inherent in the transfer of ink or colour from a preliminary distributing or working up set to a proper inking roller set, are according to the present invention obviated by the division of the preliminary distributing or working up roller set into a stationary and a swinging group of rollers, the latter group acting to transfer the ink from the stationary group, further distributing or working

up the ink and transferring same to the inking roller set. This invention, therefore, consists in interposing between the preliminary distributing or working up set of rollers which rotates continuously in the same direction and the inking roller set proper which is operated by the printing carriage, a group of distributing rollers consisting of one or more distributing drums and several composition rollers. This intermediate group assists whilst it is in contact with the preliminary set of distributing rollers in the distribution or working up of the ink, and swings at the required time once for each printing operation toward the inking roller set and transfers the worked up ink to said inking roller. Before this swinging group of distributing rollers is again brought into contact with the preliminary set of distributing rollers, the preliminary set has already sufficiently worked up or distributed the strip of ink which it has in the meantime received from the ink box by means of the lifter roller, so that the two groups of distributing rollers are enabled to co-operate and to effect a very high degree of ink distribution or working up. The advantage realized by this invention therefore consists in that the swinging group of distributing rollers being composed of several co-operating distributing rollers and composition rollers, is on the one hand capable of taking up a sufficient amount of worked up ink in a thin layer and transfer same to the inker set, and on the other hand, during contact with the preliminary distributing roller set assists in the distribution or working up of the ink. The distributing capacity of the preliminary set is, therefore, considerably increased, and ink is worked up or distributed also during the interval in which the messenger group swings from the preliminary distributing group to the inker set.

The accompanying drawing shows by way of example, two constructions embodying the features of the present invention as applied to a two-revolution fast printing press, Fig-

ure 1 being a side elevation of one construction and Figure 2 a side elevation of a modified construction.

In the construction shown in Fig. 1, the preliminary distributing roller set comprises a distributing drum *a*, a steel roller *b*, the composition rollers *c* and *d* and the swinging pick up roller *e* which picks up the ink from the ink table *f* and transfers the ink to the preliminary distributing roller set. The swinging messenger group of distributing rollers consists of a distributing drum *g*, a steel roller *h* and the composition rollers *i* and *k*. The four rollers *g*, *h*, *i* and *k* are mounted in a swinging frame *l*. The inking roller set consists of the distributing rollers *m*, *n* and *o*, the steel roller *p*, the composition rollers *q* and *r* and the inkers *s*, *t* and *u*. The distributing drum *a* of the preliminary distributing roller set and the distributing drum *g* of the swinging distributing roller group are driven from the same gear *v* which continuously rotates in the same direction. Whilst the pick up roller *e* receives ink from the ink table *f*, the swinging messenger group of distributing rollers is in contact with the inking roller set so that the preliminary distributing roller set will have distributed or worked up the strip of ink to a sufficient degree before the swinging messenger group of distributing rollers is brought into contact with the preliminary distributing roller group.

As is shown in the drawing, the pick-up roller *1* is carried by an arm adapted to rock about the shaft *o'* of the drum *a* and operated by means of a lever *b'* to which is pivoted a rod *c'*, which in turn is pivoted to a two-arm lever *e'* pivoted at *d'* and acted upon by a cam *g'* bearing against a roll *f'* carried by the said lever *e'*.

The rocking of the frame *1* carrying the rollers *g*, *h*, *i* and *k* is effected by means of an arm *h'*, a rod *i'* pivoted to said arm and a two-arm lever *l'* fulcrumed at *k'* and acted upon by a cam *m'*.

Both the cams *g'* and *m'* are mounted on a shaft making one revolution during each printing operation.

The frame carrying the drum *g* and the rollers *i*, *h* and *k* may also be arranged to swing about the axis *w* of the gear *v*. Otherwise, the arrangement may remain the same as shown in Fig. 1, and the drum *g* may be rotated by the gear *v*.

Fig. 2 shows a somewhat modified construction in which the ink transferring group is driven by a gear *x* which also drives the inking roller set. The rollers *g*, *h*, *i* and *k* of the swinging distributing roller set are in this case mounted in a frame which swings about the axis *y* of the gear *x*.

What we claim is:

1. In fast printing presses provided with a reciprocating printing carriage, a roller inking apparatus composed of an inking roller set operated by said printing carriage, and a preliminary distributing roller set, the latter set comprising a stationary group of rollers and a group of rollers adapted to rock about a common fulcrum so as to cooperate alternately with said stationary group and said inking roller set, and a means for periodically rocking said group of rollers. 70

2. The combination as specified in claim 1, in which said rocking group of rollers comprises at least one distributing roller 80 and a plurality of composition rollers.

3. The combination as specified in claim 1, in which said rocking group of rollers comprises at least one distributing roller and a plurality of composition rollers and including means for rotating said rollers. 85

4. In fast printing presses provided with a reciprocating printing carriage, a roller inking apparatus comprising an inking roller set operated by said printing carriage, a preliminary distributing roller set and an intermediate group of rollers adapted to rock about a common fulcrum, so as to alternately cooperate with said preliminary distributing roller set and said inking roller set, and a means for periodically rocking said intermediate group of rollers. 90

5. In fast printing presses provided with a reciprocating printing carriage, a roller inking apparatus comprising an inking roller set operated by said printing carriage, a preliminary distributing roller set, an intermediate group of rollers and a single frame carrying said intermediate group and pivoted to rock about a fulcrum so as to alternately move said intermediate group of rollers in contact with said preliminary distributing roller set and said inking roller set, and a means for periodically rocking said frame. 100

6. In fast printing presses provided with a reciprocating printing carriage and inking table, a roller inking apparatus comprising an inking roller set operated by said printing carriage, a preliminary distributing roller set and an intermediate group of rollers adapted to rock about a common fulcrum so as to alternately cooperate with said preliminary distributing roller set and said inking roller set, a means for periodically rocking said intermediate group of rollers, a pick-up roller cooperating with said inking table and adapted to transfer the ink therefrom to said preliminary distributing roller set, and a means for operating said pick-up roller. 115

7. In fast printing presses provided with a reciprocating printing carriage, a roller inking apparatus comprising an inking roller set operated by said printing carriage, a pre- 120

liminary distributing roller set, including a large distributing drum, and an intermediate group of rollers, including a distributing drum, adapted to rock about a common fulcrum so as to alternately cooperate with said preliminary distributing roller set and said inking roller set, a means for periodically rocking said intermediate group of rollers, and a means for simultaneously rotating the distributing drums of said preliminary distributing roller set and said intermediate group of rollers.

In testimony whereof we have affixed our signatures.

WILHELM KOLMER.
ERHARD WIRSCHINGER.
